UNITED STATES PATENT OFFICE

CHARLES H. WILD, OF BALTIMORE, MARYLAND, ASSIGNOR TO BURT MACHINE COMPANY, INCORPORATED, OF BALTIMORE, MARYLAND, A CORPORATION OF MARYLAND

CAN LABELING MACHINE

Application filed October 5, 1929. Serial No. 397,602.

In accordance with the present existing practice in the labeling of cans and similarly shaped packages, the cans or packages are rolled by a belt or other propelling means 5 along suitable ways which overlie the label pack. The cans or packages are spotted with adhesive before they reach the label pack and as each can passes over the pack, it picks up a corresponding label which is wound about the can as it rolls forward 10 through the machine. To complete the labeling operation each label is coated as to its lap end or rear end, in view of the rolling action described, with adhesive supplied 15 from a second paste receptacle known as the paste pot. Formerly, a thick adhesive was used and the paste pot was open at the top to provide for the introduction of the adhesive in solid form. The open paste pot 20 admitted more or less dirt which, being transferred to the labels, disfigured the finished packages, and, in addition to this, considerable difficulty was involved in the attempt to attain uniform distribution of the 25 adhesive on the respective labels so that comparatively close supervision of the pasting mechanism with corresponding expense in the operation of the machines was involved 30 in order to supply the adhesive in uniform charges to the respective labels in turn.

The present invention relates to an improved lap end pasting mechanism in which the feed is controlled by the cans as they pass and in which the rate of feed may be adjustable so that any desired rate of distribution can be obtained in strict proportion to the number of cans fed. Also the paste pot is preferably closed, the difficulty incident to the presence of dirt in the paste is completely overcome.

In the accompanying drawings I have illustrated a paste feeding mechanism embodying the improvements of my invention, 45 together with so much of a can labeling ma-

chine to which the same is applied as is necessary to a full understanding of the same.

In the drawings:

Figure 1 is a fragmentary side elevation of a can labeling machine looking at the same 50 from the left of the operator as he faces the machine from the feed end, the portion of the machine shown including the entire lap end pasting mechanism, and the adjacent portions of the machine.

Figure 2 is a top plan view of the same, the paste pot and can feeding belt being removed for convenience of illustration.

Figure 3 is a section on the line 3—3 in Figure 2.

Figure 4 is a side elevation of the paste pot removed, a portion of the side wall of the pot being broken away to show the internal construction.

Figure 5 is a horizontal section through 65 the paste pot on the line 5—5 in Figure 4.

Figure 6 is a vertical section on the line 6—6 in Figure 2.

Figure 7 is a fragmentary elevation of the machine from the right side of the operator, 70 showing the paste applying mechanism.

Figure 8 is a fragmentary section on the line 8—8 of Figure 3.

Figure 9 is a fragmentary bottom plan of the paste distributing nozzle, the central 75 area being removed and portions of the wall being broken away to show the internal construction.

Figure 10 is a bottom plan of the entire nozzle removed on a reduced scale.

Figure 11 is a front view of the nozzle removed showing the plug stops and the operating means therefor.

Figure 12 is a section on the line 12—12 in Figure 9, disclosing the plug and rib structure of the conduit member, together with one of its paste delivery slots.

Figure 13 is a plan view corresponding to Figure 2, showing the modified form of nozzle, the adjacent portion of the machine be- 90

ing shown in dotted lines for convenience of illustration.

Referring to the drawings by numerals, each of which is used to indicate the same or similar parts in the different figures, the construction shown, particularly in Figure 1, comprises the frame of the machine represented by side rails 1, between which are provided suitable means forming ways 2 for supporting the cans. On each side of the ways are suitable can guides or rails 3, the cans being propelled through the machine by any suitable means as a belt 4, held in contact with the cans by means of rollers 5 controlled by means of suitable roller guides 6, mounted on supports 7, all in accordance with the usual practice. Beneath the ways in registration with a suitable opening provided therein for this purpose is a label table 8 adapted to carry and support a pack of suitable labels 9.

The pasting mechanism which is the subject of the invention consists of a standpipe in the form of an upright tube 10, Figures 1 and 3, open at the top at 11 and mounted on the frame of the machine at the side adjacent and near the rear end of the label table as shown. In the form of the invention illustrated, this standpipe is provided with a depending lug 12 carrying a boss 14, which is apertured at 15 to receive a stud 16, secured to the frame in any suitable manner. As shown, the boss 14 is bored and tapped to receive a set screw 17 by means of which the standpipe is secured in position on the stud 16, the parts also being connected by a key 18 which prevents the rotation of the standpipe about the stud and locks it in upright position. The illustration also includes a paste pot 20 at the top of the standpipe. This paste pot is provided with a tubular outlet 21, integral with its bottom wall as hereinafter described. This tubular outlet 21 fits inside the open upper end 11 of the standpipe whereby the paste pot is connected to and supported on the standpipe.

The standpipe 10 is shown as formed and provided with a bulkhead 22, Figure 3, near the bottom of the upright portion 25, which bulkhead contains a port 24 leading downwardly from the upright portion 25 to the discharge portion 26. This port 24 is provided at its upper end with an upwardly disposed valve seat 27, which cooperates with a valve 28 shown as mounted to slide and constructed with a depending plug 23 which fits in the port 24, displacing its contents. Valve 28-23 is referred to as a displacement valve.

In the form of the invention shown the discharge portion 26 at the lower end of the standpipe terminates in a journal bearing portion 30, which is transverse to the direction of feed of the cans being disposed inwardly toward the center of the machine, i. e., to the right as the machine is seen from the feed end, the paste pot being in accordance

with the construction illustrated on the left side of the machine as thus viewed. This journal bearing and tubular member 30 contains a hollow shank or journal 31, which rocks therein and carries the paste nozzle or distributor 32 with which it is integral. This nozzle will be more fully described.

Referring now to the standpipe valve 28, see Figure 3, in the form of the invention shown, this valve is supported on a stem or shank 34, mounted to slide in vertical guides 35, suitably secured within the standpipe and the stem is further provided with spaced abutments or shoulders 36, engaged by a fork or other suitable means, 37, carried by a valve actuating lever arm 38, mounted on a shaft 39 which rocks in suitable bearings 40 shown as mounted on the standpipe 10. This shaft 39 extending transversely through a passage 41, which runs rearwardly from the standpipe 10 just above the valve seat 24, and terminates in a rearwardly disposed opening 42, closed by a screw plug 43. The valve actuating lever arm 38 is located in said passage 41, the fork 37 projecting forwardly therefrom, i. e., into engagement with the valve stem 34. The shaft 39 carries, in addition to the arm 38, which operates the valve 37, a rearwardly projecting operating arm 44. This arm is engaged from above by an adjusting screw 45, having a head 46 with suitable gripping means and a lock washer or collar 47 suitably keyed to the screw shaft, but adapted to slide longitudinally thereof.

This lock washer 47 is in the form of the invention shown pressed downwardly by a coil spring 48 against a threaded boss or nut 49 through which the screw is threaded. The upper edge of this boss is provided with a positioning notch 50 engaged by a positioning tooth 51 on said washer 47, or the adjusting screw may be positioned in any suitable manner. The boss or nut 49 is in turn carried by an arm 52 secured to or projecting from the carrier arm 54 of a can tread or feeler 53, which can tread or feeler extends across the path of the cans immediately adjacent the paste nozzle 32, being shown slightly to the rear thereof. The treadle or feeler arms 54, one at each side of the machine, are pivotally connected to the machine frame or to a suitable bracket thereon at 55. The treadle or feeler is held normally raised and the valve 28 is held normally closed by a coil tension spring 56 connected at one end to a suitable stationary point 57 on the machine frame and at the other end to an upwardly projecting arm 58 secured to the valve operating arm shaft 39.

It must be apparent that the standpipe valve 28 being normally closed by the spring 56, it is opened or the width of its opening is temporarily increased each time a can passes through the machine depressing the

can treadle or feeler 53. It will also be understood that passage 41 is provided for the accommodation of the valve lever 38, and that the plug opening 42-43 at the end of 5 said passage provides for the removal and reinsertion of said lever, the shaft 39 being removed and inserted at right angles thereto.

In accordance with the usual practice, the main supply of paste which is thinner than 10 that employed in accordance with the previous practice, is inserted in the reservoir 20, which is provided with a tightly fitting cover 60, see Figure 1. This paste pot also has a hand operated valve 61, having a seat 62 at 15 the upper end of the tubular outlet 21, which valve has a substantially vertical traverse, being provided with an upwardly extending stem 63, and having a handle 64 at its upper end. The stem 63 is mounted to slide in 20 vertical guides 65, supported in any suitable manner in the paste pot. This valve provides for the closing of the paste pot outlet at any suitable time.

The valve 61 also includes a depending 25 plug 60' which fits in the port 62' below the seat 62 displacing downwardly the contents of the port. In this way the plug 60' and port 62' act as a pump to fill nozzle 32 and the 30 passages leading thereto when the valve 61 and plug are moved up and down, which operation is performed manually on starting after said nozzle and passages have been emptied as for cleaning.

The construction, operation and manner 35 of mounting the nozzle 32 are also of interest. The nozzle 32 in the preferred form comprises a supply conduit 68 and a delivery or distribution conduit 69. Both of these conduits extend transversely of the can feed. 40 They are, therefore, parallel to each other and are preferably formed of a single piece of metal, as best illustrated in Figure 6. The supply and delivery passages 70 and 71, respectively, being preferably of oval cross 45 section or otherwise elongated transversely to the length and in the direction of the can feed. These passages are connected at frequent intervals throughout the length of the delivery passage 71, by short transverse passages 72. The delivery conduit 69 is shorter 50 than the supply conduit 68 and is preferably provided with a delivery slot 73 extending the entire length of its bottom wall, as best illustrated in the bottom plan, Figure 9, and 55 the section Figure 6.

The delivery of the paste through the slot is further facilitated by transverse grooves 74 in the bottom surface of the delivery conduit 69. The delivery of the paste from the 60 nozzle and particularly the length of the line over which the paste is delivered, i. e., the length of the opening of the delivery slot 73 is controlled by stops or plugs 75, see Figures 9, 10 and 11, which are inserted in the ends 65 of the passage 71, the same being left open

for this purpose. The depth or extent to which these plugs are inserted from either or both ends controls the length of the delivery slot opening. The plugs 75 in the form of the invention shown are mounted on wire 70 handles 77, see particularly Figure 11, which as shown, are formed each with a loop at the end at 78 and an arm 79, parallel to the plug which takes over the outside of the nozzle and tends to hold the corresponding plug in 75 position. The plugs 75 are shown as having ribs 75' which fit in corresponding slots 73 to close the same.

The nozzle member 32 has been described as having a hollow journal 31 through which the paste is admitted from the paste pot and standpipe 10 via the tubular journal bearing 30 at the bottom of the standpipe 10. In the form of the invention illustrated in Figures 1 to 11, this journal 31 is formed on the end of the supply conduit 70, adjacent the paste pot and the other end of the supply conduit is provided with a stud 80 in alignment with the journal 31, which stud 80 fits in a suitable bearing 81 on the machine frame 80 supported by a bracket 82, provided for this purpose and secured to the frame.

By virtue of the structure thus described, the supply nozzle 32 is mounted to rock on the bearings 30-31, 80-81 about the axis of 95 the supply conduit 68, permitting the delivery conduit 69 to swing up and down upon said axis.

Referring now to Figures 6 and 7, it will 100 be noted that there is a leaf spring or plate spring 83, on each side of the machine secured to the frame extending forwardly and normally inclined downwardly so that its forward end 84 bears against the top of the delivery conduit 69, pressing the same into close contact with the lap end 85 of the top label 86 of the pack 9, said top label being shown in Figure 6 as drawn upwardly as to its forward portion 87, the extreme end of which not illustrated in this figure has 105 been caused to adhere to the can 88 which is leaving the label pack, having passed over the same.

Figure 13 shows a modified form of nozzle. 115 In some instances where the adhesive used has been slightly too thick or for some reasons not fully understood, some difficulty has been encountered due to the partial failure of the supply of paste at the end of the nozzle remote from the paste pot. The modified form referred to is provide with means tending to overcome this difficulty. The illustration, Figure 12, includes a section through the lower part of the standpipe 100, the same being slightly modified as compared to the corresponding element 10 in Figure 8, providing an outlet at 101, leading to the secondary supply tube 102, which crosses the machine at right angles to the can feed and is connected to the supply conduit 104 of the nozzle 103 at 120 125 130

the end of the same opposite to the paste pot, the position of which is indicated by the standpipe 100, it being understood that the paste pot would overlie the standpipe. The secondary supply pipe 102 is turned backwardly upon itself at the end remote from the standpipe 100, the end 105 of the secondary supply tube 102 forming a hollow journal, which is supported in a suitable boss 106 on the frame of the machine and enters and has a running fit in the hollow journal 107 formed on the corresponding end of the supply conduit 104 of the nozzle 103 for this purpose. The other end of the nozzle is pivotally mounted as in the previously described form, being provided at the corresponding axial end with a hollow journal 108 which fits and rotates in a journal bearing 109 formed on the standpipe 100. The nozzle 103 includes in addition to the supply conduit 104, a delivery conduit 110, the conduits 104 and 109 being related as in the construction previously described.

In the operation of the machine equipped with the paste supplying means of the invention, the cans are fed by means of the belt 4 or other suitable propelling means along the ways 2, and the labels 9 are presented by means of the table 8, all in accordance with the established practice. It being assumed that the standpipe 10, the nozzle and the passages leading thereto from the standpipe have been cleaned out and the bottom outlet of the paste pot closed for the overnight period of unemployment or the like and the pastepot 20 being assumed to be full or containing sufficient adhesive, the valve 61 with its displacement plug 60' is reciprocated slowly by manual engagement of the handle 64. This operation serves to push downwardly through the port 62' sufficient paste to fill the nozzle and passages. The valve 61, including plug 60', is then raised and set screw 64' is tightened, the collar 64'' having been slid down into contact with the upper guide 65 holding the valve in open position. The paste is thus permitted to continue to flow downwardly into the standpipe 10. It being understood that the valve 28 at the bottom of the standpipe is normally closed, this valve is held open in any suitable manner to permit the discharge end 26 of the standpipe and also the nozzle 32 comprising the delivery conduit 68 and the supply conduit 69 to become completely filled with the adhesive material. When this has been done, the valve 28 is permitted to close in response to the tension of the spring 56 acting on the upwardly disposed arm 58 of the shaft 39.

The passage of the cans through the machine and over the label table brings them successively in contact with the top of the feeler 53. This feeler is narrow enough to fit in the tapered space between the cans even if they are in contact so it requires no spacing of the

cans and does not in any way affect or limit the speed of the machine, a high speed with slight spacing of the cans being almost requisite under the present practice. In the form shown the feeler is located just beyond the label table, see Figure 7, in the direction of can feed, and is mounted on the arms 54 pivoted at each side of the machine, one of which arms carries the bracket or arm 52, see Figure 1, on which a threaded head or nut 49 is formed. This nut supports and receives the adjustable pressure screw 45 by which the action of the feeler is communicated to the valve 28 opening the same or increasing the opening of the same as each can passes, it being understood that the screw 45 bears on the rearwardly extending arm 44 secured to the shaft 39, which carries the forwardly extending valve operating arm 38, and spring arm 58 engaged by spring 56 to close the valve. As the valve is thus closed after each such upward movement, a quantity of adhesive corresponding to the said upward movement is pushed downwardly toward the nozzle, by the displacement action of the plug 23 in port 24. It will thus be apparent that there is a feeding impulse for each can that passes along the ways and over the label table which feeding impulse results in a corresponding exudence of adhesive from the nozzle opening or slot 73.

In this connection, it will be apparent that as different labels of different widths are supplied to the machine, the width or rather the length of the feeding slot 73 or the effective portion thereof and the position thereof laterally of the machine, may be adjusted, varied and determined by the positions of the respective plugs 75, which are accordingly inserted or withdrawn. The paste is thus exuded from the nozzle as each can strikes the feeler 53 and the feeding impulse is transmitted from the paste pot to the outlets 73 with sufficient speed to cause the contact of each can with the feeler to result in the delivery and application of a corresponding charge of adhesive to the lap end of the label which is being taken up by the can. This relation of the parts will be apparent from Figure 6, which shows the can 88 picking up a label 86, the lap end of which 85 is still in position on the pack extending well back of the nozzle slot 74, the can being at the same time in contact with the feeler 53. It is also apparent that the nozzle being pivotally mounted as shown, the spring 83 serves to incline the nozzle member downwardly and forwardly keeping the delivery conduit 69 and the feed slot 73 thereof in contact with the top label. This has the effect of backing up and accumulating a quantity of adhesive 74' rearwardly of the slot 73. This assists in spreading the adhesive and bringing it in close contact with the end of the label adjacent the lap end thereof.

As the can 88 proceeds through the ma-

chine, the paste coated lap end 85 of the label is brought in contact with the can by the winding of the label about the can as the latter advances, and the can having completed the 5 picking up operation and passed over the feeler 53, comes next in contact with the pressing pad 90 by which the label is smoothed and pressed against the surface of the can, the contact of the label with the can being thus perfected.

The operation in the modified form of Figure 13 is in no wise different from that of the form described except that the supply conduit 104 of the nozzle is fed from both ends 15 toward the center instead of from one end of the nozzle as in the construction just described, i. e., from the standpipe 100, the paste flows to the adjacent end of the supply conduit 104 by way of the hollow journal 108 and 20 the journal bearing 109, which is connected directly to the inside of the standpipe 100 and the liquid adhesive passes to the other end of the supply conduit 104 by way of the secondary supply tube 102, which is connected at 25 101 to the standpipe 100 and at the other end at 105 to the supply conduit, the end 105 serving as a hollow journal which occupies the journal bearings 107, which is continuous with and connected to the inside of the supply 30 conduit 104.

In addition to the other improvements and improved results obtained, the new construction makes it feasible to feed a thin liquid adhesive instead of the semi-solid variety 35 previously used and to deliver the same to the labels in direct proportion to and in accordance with the number of cans fed, the feeding impulse being transmitted through the entire line, i. e., from the paste pot to the outlet of 40 the paste nozzle. According to the preferred arrangement, as each can passes from the label pack, the feeding impulse of each can serves to apply the necessary amount of paste to the lap end of the label which is being 45 taken up by that can.

Other important improvements and improved results have been fully discussed in the specification.

I have thus described specifically and in 50 detail a can labeling machine embodying the features of my invention in the preferred form in order that the nature, manner of operation and construction and using the same may be fully understood, however, the terms 55 herein are used descriptively rather than in a limiting sense and the scope of the invention is defined in the claims.

What I claim as new and desire to secure by Letters Patent is:

60 1. In a can labeling machine a lap end pasting mechanism, means for feeding cans through the machine, means for maintaining a supply of labels in the path of the can, a paste delivering nozzle in operative relation 65 to the lap end of the top label and means in

the path of the cans to be contacted by each can as it passes for transmitting a feeding impulse from said can to said nozzle and means cooperative with said feeding impulse to produce a positive ejection of the paste from said 70 nozzle in the form of an intermittently operated valve.

2. In a machine for labeling cans or packages means for feeding the cans through the machine, means for supporting a pack of labels in the path of the cans, a nozzle for discharging paste in contact with the lap ends of the labels, a paste passage leading to said delivery means an intermittently operated valve in said passage having means for positively advancing the paste, a feeler in the path of the cans and means connected to said feeler to operate the valve as each can contacts the 75 feeler.

3. In a machine for labeling cans or packages means for feeding the cans through the machine, means for supporting a package of labels in the path of the cans, a nozzle for discharging paste in contact with the lap ends of the labels, a paste passage leading to 80 said nozzle, a valve in said passage controlling and advancing the paste, a feeler in the path of the cans and means connected to said feeler to open the valve as each can contacts the feeler, said connections including a valve operating lever the paste passage having an outlet in which said lever is mounted and an opening in line with said lever through which the same may be removed.

4. In a machine for labeling cans or packages means for feeding the cans through the machine, means for supporting a package of labels in the path of the cans, a nozzle for discharging adhesive in contact with the lap ends of the labels, a paste passage leading to 100 said delivery means, a valve in said passage controlling the delivery of the paste, a feeler in the path of the cans and means connected to said feeler to open the valve as each can contacts the feeler, said feeler being provided with a screw adjustment having a stop, a valve lifting lever and an arm operating said lever engaged by said screw.

5. In a can labeling machine a lap end pasting mechanism including a nozzle for delivering the paste in contact with the lap ends of the labels, a pastepot connected to said nozzle to feed the same and a hand operated valve for closing the pastepot outlet, the same having means connected thereto for positively advancing the paste in an intermittent manner in predetermined quantities into the nozzle to fill the same.

6. In a can labeling machine a lap end pasting mechanism including a nozzle, a pastepot connected to the nozzle to feed the same with liquid paste, a valve controlling and advancing the paste toward the nozzle, a spring tending to operate the valve in one direction, means for operating the valve in 105 110 115 120 125 130 135 140 145 150 155 160 165 170 175 180 185 190 195 200 205 210 215 220 225 230 the opposite direction a feeler in the path of the cans and adjustable means connected to the feeler for communicating the motion of the feeler to said means as each can passes.

5 7. In a lap end pasting mechanism for can and similar labeling machines a label support, a nozzle adjacent said support, means for supplying liquid adhesive to the nozzle, said nozzle comprising a plurality of conduits, transverse to the can feed and spaced apart in the direction of the feed, one said conduit having its ends pivotally mounted and serving as a supply conduit, the other said conduit serving as a delivery conduit swinging about said supply conduit on said ends as an axis, means for determining the comparative length of said slot, comprising a plug fitting in the delivery conduit and adjustable in the direction of the length thereof.

10 15. supply conduit on said ends as an axis and into contact with the lap end of the top label on said support.

15 8. In a lap end pasting mechanism for canning and similar labeling machines a nozzle, means for supplying liquid adhesive to the nozzle, said nozzle comprising a plurality of conduits, transverse to the can feed and spaced apart in the direction of the feed, one said conduit having its ends pivotally mounted and serving as a supply conduit, the other said conduit serving as a delivery conduit swinging about said supply conduit on said ends as an axis, means for adjusting the length of said delivery means.

20 25. mounted and serving as a supply conduit, the other said conduit serving as a delivery conduit swinging about said supply conduit on said ends as an axis, said delivery conduit having a slot in its bottom and means for maintaining the same in contact with the lap ends of the labels.

25 30. 9. In a lap end pasting mechanism for canning and similar labeling machines a nozzle, means for supplying liquid adhesive to the nozzle, said nozzle comprising a plurality of conduits, transverse to the can feed and spaced apart in the direction of the feed, one said conduit having its ends pivotally mounted and serving as a supply conduit, the other said conduit serving as a delivery conduit swinging about said supply conduit on said ends as an axis.

35 35. 10. In a lap end pasting mechanism for canning and similar labeling machines, a can feed, a nozzle, means supporting a label pack in the path of the cans, means for supplying liquid adhesive to the nozzle, said nozzle having a discharge opening in its bottom surface and means supporting the nozzle with its bottom surface inclined upwardly from said opening in the direction of feed, and means for maintaining the opening in contact with the top label slightly forward of its lap end.

40 45. 11. In a lap end pasting mechanism for can and similar labeling machines a nozzle, means for supplying liquid adhesive to the nozzle in an intermittent manner and in predetermined quantities, said nozzle having a slot in its bottom surface, and means for maintaining the same in contact with the lap ends of the labels, the bottom surface of the delivery conduit being also slotted transversely to said aforementioned slot.

50 55. 12. In a lap end pasting mechanism for

canning and similar labeling machines a nozzle, means for supplying liquid adhesive to the nozzle, said nozzle comprising a plurality of conduits, transverse to the can feed and spaced apart in the direction of the feed, one said conduit having its ends pivotally mounted and serving as a supply conduit, the other said conduit serving as a delivery conduit swinging about said supply conduit on said ends as an axis, means for determining the comparative length of said slot, comprising a plug fitting in the delivery conduit and adjustable in the direction of the length thereof.

60 65. 13. In a lap end pasting mechanism for canning and similar labeling machines a nozzle, means for supplying liquid adhesive to the nozzle in intermittent forced quantities, said nozzle comprising a conduit transverse to the can feed, said conduit having delivery means arranged in the direction of its length, means for adjusting the length of said delivery means.

70 75. 14. In a lap end pasting mechanism for canning and similar labeling machines a nozzle, means for supplying liquid adhesive to the nozzle, said nozzle comprising a conduit, transverse to the can feed, said conduit having delivery means arranged in the direction of its length, means for adjusting the length of said delivery means comprising a plug fitting in each end of the conduit and adjustable in the direction of the length thereof each of said plugs having integrally mounted thereon ribs that engage the slot opening in the nozzle for the purpose of limiting the flow of paste from each end of said slotted portion of the nozzle member.

80 85. 15. In a lap end pasting mechanism for canning and similar labeling machines a nozzle, means for supplying liquid adhesive to the nozzle, said nozzle comprising a plurality of conduits, transverse to the can feed and spaced apart in the direction of the feed, one said conduit having its ends pivotally mounted and serving as a supply conduit, the other said conduit serving as a delivery conduit swinging about said supply conduit on said ends as an axis, means for determining the comparative length of said slot, comprising a plug fitting in the delivery conduit and adjustable in the direction of the length thereof, said plug having an external rib fitting in said slot.

90 95. 16. In a lap end pasting mechanism for a can labeling machine having means for feeding cans through the machine, a support for a label pack in the path of the cans, a paste-pot, a standpipe leading downwardly therefrom, a nozzle extending transversely to the can feed in pasting relation to the top of the label pack, and connected to said conduit to receive paste therefrom, the said connection comprising a hollow journal and a journal bearing, one said member being connected to

the standpipe and the other said member to the nozzle, pivotal means supporting the other end of the nozzle in line with the axis of said journal.

- 5 17. In a lap end pasting mechanism for a can labeling machine having means for feeding cans through the machine, a support for a label pack in the path of the cans, a paste-pot, a standpipe leading downwardly therefrom, a nozzle extending transversely to the can feed in pasting relation to the top of the label pack and connected to said conduit to receive paste therefrom, the said connection comprising a hollow journal and a journal bearing, one said member being connected to the standpipe and the other said member to the nozzle, pivotal means supporting the other end of the nozzle in line with the axis of said journal, a can feeler in the path of 15 the cans, a valve controlling the paste supply to the nozzle and means connecting said feeler to said valve to control the paste feed.
18. In a lap end pasting mechanism for can labeling machine having means for feeding cans through the machine, a label support in the path of the cans, a paste pot, a standpipe leading downwardly therefrom, a nozzle extending transversely to the can feed and connected to said conduit to receive paste 20 therefrom, the said connection comprising a hollow journal and a journal bearing, one said member being connected to the standpipe and the other said member to the nozzle, pivotal means supporting the other end 25 of the nozzle in line with the axis of said journal, said nozzle including a delivery member also extending transversely to the feed and connected to said journal to swing about the center thereof in contact with the 30 labels.
19. In a can labeling machine having means for feeding the cans through the machine, means for supporting the labels in the path of the cans, a delivery nozzle extending 35 transversely to the can feed at the front of the table, pivotal means at each end of said nozzle comprising a hollow journal at each end of said nozzle for feeding paste to both ends of the nozzle at the respective sides of 40 the machine.

20. In a machine for labeling cans or packages, means for feeding the cans, means for supporting a pack of labels in the path of the cans, a nozzle for discharging paste in 45 contact with the lap ends of the labels, means for positively feeding adhesive to the nozzle and a can feeler in the path of the cans controlling said positive feed, said feeler being of less dimension in the direction of the 50 feed than the space between the lower portion of the cans when they are in contact in the direction of feed, avoiding any limitation as to the spacing of the cans.

21. In a machine for labeling cans or packages means for feeding the cans through the

machine, means for supporting a pack of labels in the path of the cans, a nozzle for discharging paste in contact with the lap ends of the labels, a paste passage leading to said delivery means, an intermittently operated valve in said passage having means for positively advancing the paste, a feeler in the path of and operating on the periphery of the cans and means connected to said feeler to operate the valve as each can 70 contacts the feeler.

Signed by me at Baltimore, Maryland, this 30th day of September, 1929.

CHARLES H. WILD.
